COMBINED EXERCISER AND WHIRLING TOY

William Margolin and Mildred Margolin, both of 829
Coffman Drive, Montebello, Calif. 90640

Filed Nov. 29, 1971, Ser. No. 203,125

Term of patent 14 years

Int. Cl. D21—01, 02

U.S. Cl. D34—15 BB

FIG. 2.

FIG. 3.

FIG. 4.

FIG. 1 is a front perspective view of a combined exerciser and whirling toy showing our new design;

FIG. 2 is a front elevational view thereof on an enlarged scale, the rear being a mirror image thereto;

FIG. 3 is a top plan view thereof, the bottom being a mirror image thereto;

FIG. 4 is a right end elevational view thereof, the left end being a mirror image thereto.

We claim:

The ornamental design for a combined exerciser and whirling toy, substantially as shown and described.
